INVERTED TURBINE

Max D. Green, 1998 Ave. Q, Phoenix, Ariz.
Filed Dec. 3, 1959, Ser. No. 856,994
3 Claims. (Cl. 253—165)

This invention is directed to an inverted turbine wherein the source of power to drive it is mounted within the axis of rotation of the main impeller wheel.

One of the objects of this invention is to provide a turbine in which the source of power to drive it is mounted within the periphery and inside of the main impeller wheel.

Still another object of this invention is to provide a turbine in which the source of power to drive the turbine can be provided through the axis of the central support members of the turbine wheel.

Still another object of this invention is to provide an inverted turbine of the above described character in which the shape of the blades are so arranged that it may be revolved in either direction by reversing the direction of power against the sides of the turbine blades.

Still another object of this invention is to provide in a turbine structure as recited above a closure ring within the turbine wheel so as to form a chamber which encloses the turbine blades, thus providing a totally enclosed operating circuit for the turbine.

Still another object of this invention is to provide in a totally enclosed turbine structure just recited above a power supply line and a return or exhaust line in order to revolve the turbine wheel in opposite directions, the combination of the two lines being such that the line not being used as a pressure line when the turbine wheel is revolved in one direction is used as a return or exhaust line to remove the fluid from the turbine chamber, and vice versa when the turbine is revolved in the opposite direction.

Still another object of this invention is to provide a totally enclosed turbine structure as recited above in which greater efficiency of power is obtained and no loss of fluid during its operation thus making possible the use of a pressure system in which it is desired to retain the fluid used and return it to the original supply to be reused again in the operation of the device.

Still another object of this invention as recited above in connection with a totally enclosed structure is in the combination of features mentioned above so that a minimum amount of lines and passageways are required and a considerably simplified structure results.

And it is to be further noted that when seals are used to retain the pressure fluid in the above mentioned totally enclosed structure and the pressure fluid is of the lubricant type, the bearings of the device are self-lubricated from the pressure fluid when such seals are in use.

Still another object of this invention is to provide a combination of control valves that permits control of the turbine wheel from one central controlled area so that the turbine wheel can be operated at various speeds in either direction and stopped due to this combination of valves from the central control.

Another object of this invention is that the ratio of the turbine blades to the number of pressure lines used is such as not to be divisible by the number of lines in use, or if they are divisible, then to convey pressure fluid to the turbine blades by lines or ports unevenly spaced circumferentially about the turbine wheel, to thus provide smoother operation and an increase in the number of power pulsations for quieter vibration free operation.

It is also an object of this invention to construct a turbine wheel with totally enclosed sides so that the pressure fluid is held directly within the turbine wheel

2

so as to place all of the power from the pressure fluid upon the turbine wheel.

Another object of this invention is to arrange the turbine wheel so that it revolves around a tubular axis and maintains itself on said axis by the balance of pressures being exerted on the turbine blades from within the turbine wheel. Thus the turbine wheel is substantially positioned on the proper axis of rotation without requiring any particular bearing guide means between the wheel and the tubular supporting frame structure.

Further features and advantages of this invention will appear from a detailed description of the drawings in which:

FIG. 1 is an enlarged sectional view of a turbine incorporating the features of this invention.

FIG. 2 is an enlarged sectional view on the line 2—2 of FIG. 1.

FIG. 3 is an enlarged sectional view on the line 3—3 of FIG. 1.

FIG. 4 is an end elevation of the turbine illustrated in FIGS. 1, 2 and 3.

FIG. 5 is a fragmentary enlarged section of the control valve on the line 5—5 of FIG. 3.

FIG. 6 is a fragmentary enlarged section of the control valve on the line 6—6 of FIG. 3.

FIG. 7 is a fragmentary enlarged section of the control valve on the line 7—7 of FIG. 3.

FIG. 8 is a perspective view of the valve components shown in FIGS. 3, 5, 6 and 7.

FIG. 9 is an enlarged sectional view of a modification showing a totally enclosed turbine wheel structure incorporating the features of this invention.

FIG. 10 is a fragmentary section of the apparatus taken on the line 10—10 of FIG. 9.

FIG. 11 is an enlarged fragmentary view of the centralized control mechanism for the turbine.

FIG. 12 is an enlarged diagram partly in section showing the control adjustment for neutral.

FIG. 13 is an enlarged diagram partly in section showing the control adjustment for forward turbine rotation.

FIG. 14 is an enlarged diagram partly in section showing the control adjustment for reverse turbine rotation.

FIG. 15 is an enlarged diagram partly in section showing the control adjustment for braking of the turbine.

As an example of one embodiment of this invention there is shown a turbine having a base 20 to which is fixed the upstanding supports 21 having the bore 22 in which is fixed tubular support member 23 to which are fixed the radially disposed supports 24 on the outer ends of which are fixed the spacer bushings 25. Annular side plates 26 are fixed to the bushings 25 by suitable rivets 27, the plates 26 being further supported in spaced relationship by the bushings 28 and rivets 29.

The turbine wheel 30 comprises an annular ring 31 having a peripheral surface 32 over which may operate a power take-off belt 33 while the interior bore 34 is provided with a series of radially inwardly extending impeller blades 35 having side faces 36 rotating between the inner faces 37 of the side plates 26. The side faces 36 are recessed below the outside faces 38 of the turbine wheel 30 so as to form surfaces 39 which may rotatably engage the peripheral surfaces 40 of the annular side plates 26.

Forward discharge jet tubes 41 are fixed at their inner ends to the tubular member 23 and are in communication with the interior bore 42 of the member 23 through the ports 43. The outer ends of the tubes 41 are suitably supported in brackets 44 attached to the side plates 26 and terminate in discharge ends 45 which direct fluid pressure to the impeller surfaces 46 of the blades 35 for forward driving rotation of the turbine wheel 30. Sim-

ilarly, the reverse drive tubes 47 have their inner ends 48 fixed to the tube 23 and in communication with the bore 42 thereof through the ports 49 while the outer ends of the tubes 47 are supported on suitable brackets 50 on the side plates 26 and have discharge ends 51 for directing fluid pressure against reverse rotation impeller surfaces 52.

Within the bore 42 of the tubular support member 23 is rotatably journaled the tubular valve 53 having an operating knob 54 for rotating the valve 53 in the member 23. A stop pin 55 is fixed in the member 23 and projects inwardly into a segmental groove 56 formed in peripheral surface 57 of the valve 53 so as to limit rotation of the valve 53 to a partial rotation by the knob 54. Connected to the pressure supply port 58 formed in the tubular support member 23 is a suitable fluid pressure supply line 59, the port 58 in turn being in communication with the interior chamber 60 of the valve 53. A pair of forward ports 61 are formed in the valve 53 in communication with the chamber 60 and adapted to register with the ports 43 when the valve is rotated to one end of slot 56 and to close off said ports when the valve 53 is rotated to the other side of slot 56 as stopped by the pin 55. Similarly, a pair of reverse ports 62 are formed in the valve 53 in communication with the chamber 60 and adapted to register with the ports 49 when the valve is rotated to the end of slot 56 and to close off said ports when the valve 53 is rotated to the other side of slot 56 as stopped by the pin 55. It is to be noted that the ports 43-61 and 49-62 are so arranged that either one or the other group are connected to the chamber 60 and fluid pressure supply line 59 when knob 54 is manipulated to one or the other direction of rotation and that when in an intermediate position, fluid pressure is cut off from both sets of ports for non-rotation of the turbine wheel. Manipulating the valve knob 54 either side of said intermediate said non-rotation position effects control of both flows for braking the turbine wheel.

In FIGS. 9 through 15 inclusive is shown a modification of the apparatus already described above in which there is provided a totally enclosed fluid pressure system for actuating the turbine wheel. In this arrangement a power unit frame 63 is supported on a suitable base 64. The side plates 65 are securely riveted at 66 to the discharge port ring 67 having the forward discharge ports 68 arranged to discharge against the blades 70 of the turbine wheel 71. In this arrangement, FIG. 10, the turbine wheel is guided between the surfaces 72 of the side plates 65 while suitable seals 73 are provided between the surfaces 74 of the turbine wheel and the surfaces 75 of the sealing rings 76 suitably fixed to the side plates 65 so as to provide a totally enclosed sealed chamber for the pockets 77 formed between the blades 70 of the turbine wheel.

Referring to FIG. 9, it will be noted that the circumferential spacing of the pockets 77 and the discharge and exhaust ports 68-69 is such that a uniform back pressure in the main supply line 81 results. For example, on the left hand side of FIG. 9 it will be noted that the forward discharge port is in communication with the discharge port 69 through a pocket 77 while on the right hand side of FIG. 9 it can be seen that the ports 68 and 69 are blocked off by a blade 70, this condition alternating back and forth at varying degrees as the turbine wheel rotates resulting in a smooth continuous flow of fluid through the device with no upsurges of back pressure against the pump 78. When the number of turbine blades used is not divisible by a whole number by the number of pressure ports used to revolve the turbine in any one direction, the pressure ports are evenly spaced circumferentially about the turbine wheel, thus the pressure against the turbine blades is not directed on any two turbine blades at the same point on the blades. When the number of turbine blades is divisible by a whole number by the number of pressure ports used to revolve the

turbine wheel in any one direction, the pressure ports are unevenly spaced circumferentially about the turbine wheel so that the pressure against the turbine blades is not directed on any two turbine blades at the same point on the blades.

Fluid pressure for actuating the just described modification is derived from a fluid pressure pump 78 mounted on the frame 63 which is driven from a suitable prime mover such as an electric motor 79 mounted on the frame 63 and connected by a suitable belt 80 to the pump 78. The fluid pressure line 81 from the pump 78 is connected to the intake port 82 of the control valve 83. Port 84 of valve 83 is connected by line 85 and the multiple connection 86 and lines 87 to the ports 68 in the ring 67. Line 85 is also connected to line 88 which is connected to port 89 of valve 90. The intake line 91 of the pump 78 is connected to port 92 of the valve 90 and also through line 93 to the fluid reservoir 94. A line 95 is interconnected between port 96 of valve 83 and port 97 of valve 90. A pressure relief valve 98 is connected into line 95 and discharges excessive pressure therefrom into the line 99 connected to line 91 of the pump. Line 95 is connected through line 100 to the multiple connector 101 to the lines 102 connected to the ports 69 of the ring 67.

Both of the control valves 83 and 90 have rotatable tubular members 103 and 104 with appropriate porting oriented relative to the ports of these valves for operation as will be described. The members 103 and 104 each have arms 105, FIG. 11, fixed thereto which are pivotally connected at 106 to the cross arm 107 having a pin 108 fixed intermediate its ends operating in an elongated slot 109 in the control lever 110 pivotally mounted on a suitable pin carried on the frame 63. The upper end of the control lever 110 has a snap pin 112 urged by a suitable spring 113 into the various detent notches 114, 115, 116, 117 and 118 formed in the arcuate control bar 119 suitably fixed to the frame 63.

When the control lever 110 is positioned in notch 114, FIG. 11, the device is set in neutral as shown in FIG. 12, fluid circulating through valve 83, lines 85 and 95, valve 90 and through the pump 78 as indicated by the flow arrows in the diagram. When the lever is in notch 115 the circuit is conditioned for flow as shown in FIG. 13 for clockwise rotation.

FIG. 14 shows the flow pattern with the lever 110 in notch 116 for counterclockwise operation. Brake condition is shown in FIG. 15 with lever in notch 118 (or 117 as the case may be) locking the turbine wheel against rotation.

While the apparatus herein disclosed and described constitutes a preferred form of the invention, it is also to be understood that the apparatus is capable of mechanical alteration without departing from the spirit of the invention and that such mechanical arrangement and commercial adaptation as fall within the scope of the appendant claims are intended to be included herein.

Having thus fully set forth and described this invention what is claimed and desired to be obtained by United States Letters Patent is:

1. In combination in a turbine structure comprising a rotatable turbine wheel having a bore and circumferentially spaced pockets separated by blades formed in said bore, a discharge port ring located in said bore including circumferentially spaced pairs of forward and reverse ports formed in said ring opening adjacent the bore of said turbine wheel, the circumferential spacing of said pockets, blades and said pairs of forward and reverse ports being so arranged that a pair of forward and reverse ports are alternately interconnected by a single pocket and isolated from each other by said blades between adjacent pockets during rotation of said turbine wheel.

2. In combination in a turbine structure comprising a rotatable turbine wheel having a bore and circumfer-

entially spaced pockets separated by blades formed in said bore, a discharge port ring located in said bore including circumferentially spaced pairs of forward and reverse ports formed in said ring opening adjacent the bore of said turbine wheel, the circumferential spacing of said pockets, blades and said pairs of forward and reverse ports being so arranged that a pair of forward and reverse ports are alternately interconnected by a single pocket and isolated from each other by said blades between adjacent pockets during rotation of said turbine wheel, said turbine structure including a plurality of circumferentially disposed pairs of said forward and reverse ports so arranged that at all times during the rotation of said turbine at least one pair of forward and reverse ports are interconnected through a pocket.

3. In combination in a turbine structure comprising a rotatable turbine wheel having a bore and circumferentially spaced pockets separated by blades formed in said bore, a discharge port ring located in said bore including circumferentially spaced pairs of forward and reverse ports formed in said ring opening adjacent the bore of said turbine wheel, the circumferential spacing of said pockets, blades and said pairs of forward and reverse ports being so arranged that a pair of forward and reverse ports are alternately interconnected by a single pocket and isolated from each other by said blades between adjacent pockets during rotation of said turbine wheel, said turbine structure including a plurality of circumferentially disposed pairs of said forward and reverse ports so arranged that at all times during the rota-

5

tion of said turbine at least one pair of forward and reverse ports are interconnected through a pocket, and a reversing control valve including means for manipulating said valve means to reverse the flow for each pair of forward and reverse ports to change the direction of rotation of said turbine wheel.
